UNITED STATES PATENT OFFICE.

ROBERT W. THOMPSON, OF PITTSBURG, PENNSYLVANIA, ASSIGNOR TO
J. FULTON THOMPSON, OF SAME PLACE.

IMPROVEMENT IN SAW-GUMMERS.

Specification forming part of Letters Patent No. 131,834, dated October 1, 1872.

To all whom it may concern:

Be it known that I, ROBERT W. THOMPSON, of Pittsburg, in the county of Allegheny and State of Pennsylvania, have invented a new and Improved Saw-Gummer, of which the following is a specification:

Figure 1 is a sectional elevation of my improved saw-gummer. Fig. 2 is an inverted end view of the cutting tool.

Similar letters of reference indicate corresponding parts.

This invention relates to a new saw-gumming apparatus for circular saws; and it consists in the combination of a rotary cutting tool with a tubular feed-screw in such manner that by means of the screw the tool can be let down more or less to cut through the entire blades, even as its points become shorter. By the screw the pressure of the cutting-tool upon the saw-blade can also be increased at will.

A in the drawing represents the frame of my improved saw-gumming apparatus. It is made in form of a yoke, with a bed-plate, *a*, to it, and is open at the sides and in front for the insertion of the saw-blade. B is a tube, screwed into the frame from above to be at right an-

gles to the bed-plate *a*. C is a pin, fitted through the tube B, and carrying at its lower end a head or enlargement, *b*, which is grooved at the bottom to receive four, more or less, cutting-teeth, *d d*, and their shanks. A sleeve, *e*, which embraces the head *b*, holds the shanks of the teeth *d* confined in the head. The saw-blade to be gummed is placed on the bed-plate *a* and fastened upon the same by screws *f f*, which are fitted through the yoke A. The pin C is then turned by means of a crank-handle at the upper end, and fed down at the same time by turning the screw B, which bears on the head *b*. In this manner the desired recess can be rapidly cut out.

Having thus described my invention, I claim as new and desire to secure by Letters Patent—

The series of cutting-teeth *d* fastened between a circular head, *b*, and sleeve *e*, as and for the purpose described.

ROBERT W. THOMPSON.
